Primary Examiner — April Rivas(74) *Attorney, Agent, or Firm* — Gregory L. Mayback; Mayback IP Law, P.A.(57) **CLAIM**

The ornamental design for a duffle, as shown and described.

DESCRIPTION

FIG. 1 is a front perspective view from a right side of a duffle showing my new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is top plan view thereof;

FIG. 7 is a bottom plan view thereof; and,

FIG. 8 is a front elevation view thereof from a right side; the broken lines of a logo in this figure illustrate portions of the duffle that form no part of the claimed design.
